UNITED STATES PATENT OFFICE.

GILBERT P. RITTER, OF CHICAGO, ILLINOIS.

COUPLING-RELEASE RIGGING.

SPECIFICATION forming part of Letters Patent No. 743,560, dated November 10, 1903.

Application filed August 25, 1903. Serial No. 170,748. (No model.)

To all whom it may concern:

Be it known that I, GILBERT P. RITTER, a citizen of the United States, residing at Chicago, in the county of Cook and State of Illinois, have invented a certain new and useful Improvement in Coupler-Release Rigging; and I hereby declare the following to be a full, clear, and exact description of the same, reference being had to the accompanying drawings, in which—

Figure 1 is a vertical central section of a release-rigging embodying my invention, the uncoupling-lever and quick-release lever being in elevation and showing the application of the device to the end of a car. Fig. 2 is a front elevation of the release-rigging, showing the relative arrangement of the several parts. Fig. 3 is a side elevation of the release-rigging shown as attached to the car-body and showing the relation of the coupler with respect thereto. Fig. 4 is a modification showing in a view similar to Fig. 1 a flexible connection between the uncoupling-lever and the piston in lieu of the rigid connection shown in Fig. 1.

Like symbols refer to like parts wherever they occur.

In making up trains, in cutting cars out of a train and placing them on side tracks, and in all switching of cars it is desirable that the manual operations of the coupler should be minimized, and to accomplish this purpose under certain conditions couplers having the well-known lock-set and knuckle-opener features are extensively used. Lock-sets and knuckle-openers operate successfully when the car to which the coupler is attached is not in motion; but in the more dangerous handling of cars while in motion such auxiliary devices are uncertain in performing their functions and being uncertain are commonly not depended upon, the desired result being attained manually.

In cutting a car out of a train and putting it upon a side track one of the couplers between the car to be cut out and the adjacent car nearer the locomotive is unlocked and the car is then backed onto the side track. During this operation and by reason of the fact that the locomotive does not push steadily and also that it is at times necessary to

return and give the car that is being cut out a second push after what was intended to be the final impulse has been given there is a constant vibration of the knuckle of the unlocked coupler, such movement being frequently so extended that the knuckle is fully opened.

Since lock-sets are all controlled by the vibration of the knuckle, some by a slight movement of the knuckle, but all by a full opening movement, it is apparent that the vibrations of the knuckle heretofore referred to actuate the lock-set to allow the lock to operate when the knuckle in its vibratory movements assumes a locked position and that the coupler is again locked and the cars cannot be separated without a further manual unlocking of the coupler. It therefore results that in switching of this character the switchman usually runs beside the car and holds the coupler unlocked by means of the uncoupling-lever, (an exceedingly dangerous practice,) as to lock the uncoupling-lever up would be to render an auxiliary lock-set device useless, and in many types of couplers having knuckle-openers the vibration of the knuckle acting upon the knuckle-opener would, if the uncoupling-lever were locked up, break either the knuckle-opener or the uncoupling-chain connected to the uncoupling-lever.

To overcome the several objections above noted is the object of the present invention, and in what manner it is accomplished will be hereinafter more particularly described and finally pointed out in the claims.

Generally stated, my invention consists in controlling the coupler-locking mechanism by means independent of the knuckle, so that said locking mechanism may be held in an unlocked position during any desired interval and may then be automatically returned to a locked position, and preferably the special means employed embrace a fluid or equivalent mobile medium and a leak therefor, together with suitable devices independent of the coupler mechanism, which devices are actuated by the first-named medium and when so operated control the locking mechanism of the coupler.

I will now proceed to describe my inven-

tion more fully, so that others skilled in the art to which it appertains may apply the same.

In the drawings of the form of device chosen to illustrate my invention, 1 is an uncoupling-lever, to which is attached by the uncoupling-chain 1^a or other suitable means the locking mechanism 2^a of the coupler 2. Various characters of these instrumentalities and their relative arrangement and attachments being well known, any of which may be adopted, they need not herein be further described. Secured to the car at any convenient and suitable point and in any suitable manner is a cylinder 3, having therein a piston, the head of which is preferably composed of separable sections 4^a 4^b, between which is the cupped packing element 4^c, which may be of any suitable material, and the piston-head is preferably secured to the piston rod or stem by and between the nut 4^d and shoulder 4^e of the piston-rod; but any form or construction of piston-head may be employed.

Within the cylinder 3 and surrounding the piston-rod above the piston-head is a spring 3^s, which when the piston has been displaced returns the same to its normal position.

To the end of the piston-rod, at the end opposite the piston-head and in any suitable manner, is secured a cross-head 5, said cross-head sliding in the guideways 3^a 3^a of the cylinder 3. Interposed between the uncoupling-lever 1 and the cross-head 5 and pivotally attached to each is the rigid connecting member 6, through which the piston is actuated by the movement of the uncoupling-lever 1 and which also coacts with the uncoupling-lever 1 and uncoupling-chain 1^a in such manner that the movement of the piston controls the movement of the coupler-locking mechanism 2^a.

If desired, a flexible and inextensible connection 6^a, as shown in Fig. 4, may be substituted between cross-head 5 and uncoupling-lever 1 in lieu of the rigid connection 6, so that the coupler-locking mechanism 2^a may be actuated by the uncoupling-lever 1 independently of the piston.

The cylinder 3 is provided with a valve 7, which connects the interior of the cylinder with the atmosphere, said valve having a leak therein, which is or may be graduated in size by a rotatable plug or cock 7^a, having a passage therethrough, 7^b being a valve-cage secured to the cylinder 3, whereby the valve is guided and limited in its opening movement.

Opening into the cylinder 3 between the piston-head in its bottomed position and the valve 7 is the fluid-pressure pipe 8, which preferably takes its pressure from the train-pipe system, said pressure-pipe 8 having therein a two-way cock of any approved construction which controls the admission of pressure to the cylinder beneath the piston-head and the connection of said cylinder 3 through the pipe 8 with the atmosphere, thus exhausting

the cylinder and accelerating the return of the piston to its normal position, and consequently also accelerating the return of the coupler-locking mechanism to a locked position, thereby controlling the period of such return movement.

For the purpose of accelerating the return of the coupler-locking mechanism to a locked position independently of the opening of the two-way cock 8^a to the atmosphere a release lever or crank 9 is attached to the car by suitable bracket-irons, said lever having an arm 9^a, which when the lever is actuated opens the valve 7 by pressing upon the stem thereof, thus exhausting the cylinder to the atmosphere and allowing the quick return of the piston to its normal position, which corresponds to a locked position of the coupler-locking mechanism, and in this manner also the period of return movement of the coupler-locking mechanism may be controlled. This latter form of quick-release mechanism is not so readily available in constructions wherein the valve and leak are located in the piston-head rather than in the cylinder-head.

It is apparent that the device may be used to perform its several functions whether the car to which it is attached is a part of a train having train-pipe pressure or whether the car has no such pressure available, for the piston may be actuated to the same purpose by a proper manipulation of the two-way cock 8^a or by the operation of the uncoupling-lever 1 and release-lever 9.

The construction being substantially such as hereinbefore pointed out, the device will operate as follows: The rotatable plug having been adjusted to graduate the leak in the valve 7 to the desired size, which determines the interval between the setting and operation of the devices, the coupler-locking mechanism may be brought to an unlocked position by momentarily opening the cock 8^a to the source of fluid-pressure, thus causing an upward movement of the piston and a compression of the spring 3^s, which movement is transmitted to the coupler-locking mechanism through the cross-head 5, connection 6, and uncoupling-lever 1, the valve 7 being held seated by the fluid-pressure, or the coupler-locking mechanism may be brought to an unlocked position by manually actuating the uncoupling-lever 1, thus causing an upward movement of the piston and a compression of the spring 3^s through the agency of the rigid connection 6 and cross-head 5,

the valve 7 opening on the upward movement of the piston by reason of the reduced pressure within the cylinder and being seated at the beginning of the return movement thereof. In this the upper position of the piston the coupler-locking mechanism is in such relation to the tail of the coupler-knuckle that said piston may descend a measurable distance without permitting the coupler-locking mechanism to lock the knuckle, the rapidity

of the descent of the piston being controlled by the size of the leak 7^a in the valve 7. The return of the piston to its normal or bottomed position is effected by the spring 3^b, said return being gradual owing to the cushioning of the air beneath the piston, the cushioning pressure gradually decreasing as the air escapes through the leak 7^a, and until the piston has descended through a portion of its stroke the knuckle is free to vibrate in or out to its fullest extent, as before explained.

In case it is desired to quickly release the cushioning-pressure from beneath the piston and to allow the immediate locking of the coupler after the piston has assumed its upper position, the same may be effected by manipulating the two-way cock 8^a to connect the cylinder 3 with the atmosphere, or the release-lever 9 may be operated to cause the inner arm 9^a thereof to contact the projecting stem of the valve 7 and open the same, thus exhausting the cylinder into the atmosphere.

While a coupler having a particular form of locking mechanism has been chosen to illustrate my invention, it is evident that any form of such locking mechanism may be employed and that many changes in details of construction may be made without departing from the scope of my invention.

It is apparent that in some forms of construction the valve and leak may be located in the piston-head instead of in the cylinder; but the same is not so desirable when the quick-release mechanism is employed.

Wherever in the claims the locking mechanism is stated to be returned to a locked position, the same shall be understood to also mean the automatically-controlled return of such locking mechanism to a position in which a subsequent movement of the knuckle causes a locking of the coupler.

Having thus described my invention, what I claim, and desire to secure by Letters Patent, is—

1. In a coupler-release rigging, the combination with a coupler having a pivoted knuckle and locking mechanism therefor, of means independent of said knuckle for retaining the locking mechanism in an unlocked position and automatically returning said locking mechanism to a locked position, substantially as and for the purposes specified.

2. In a coupler-release rigging, the combination with a coupler having a pivoted knuckle and locking mechanism therefor, of means independent of said knuckle for retaining the locking mechanism in an unlocked position and automatically returning said locking mechanism to a locked position, and means for controlling the period of the return movement of the locking mechanism to a locked position, substantially as and for the purposes specified.

3. In a coupler-release rigging, the combination with a coupler and the locking mech-

nism therefor, of means independent thereof for automatically returning said locking mechanism to a locked position after the same has been set in an unlocked position, substantially as and for the purposes specified.

4. In a coupler-release rigging, the combination with a coupler and the locking mechanism therefor, of means independent thereof for automatically returning said locking mechanism to a locked position after the same has been set in an unlocked position, and means for controlling the period of the return movement of the locking mechanism to a locked position, substantially as and for the purposes specified.

5. In a coupler-release rigging, the combination with a coupler and the locking mechanism therefor, of elastic means whereby the locking mechanism is retained in an unlocked position and automatically returned to a locked position, substantially as and for the purposes specified.

6. In a coupler-release rigging, the combination with a coupler and the locking mechanism therefor, of elastic means whereby the locking mechanism is retained in an unlocked position and automatically returned to a locked position, and means for controlling the period of the return movement of the locking mechanism to a locked position, substantially as and for the purposes specified.

7. In a coupler-release rigging, the combination with a coupler and the locking mechanism therefor, of fluid-pressure means whereby the locking mechanism is retained in an unlocked position and gradually and automatically returned to a locked position, substantially as and for the purposes specified.

8. In a coupler-release rigging, the combination with a coupler and the locking mechanism therefor, of a cylinder, a piston in said cylinder, and means whereby the movement of the piston controls the coupler-locking mechanism, substantially as and for the purposes specified.

9. In a coupler-release rigging, the combination with a coupler and the locking mechanism therefor, of an uncoupling-lever connected to said locking mechanism, and means whereby the uncoupling-lever actuates the coupler-locking mechanism to bring the latter to an unlocked position and to automatically return the same to a locked position, substantially as and for the purposes specified.

10. In a coupler-release rigging, the combination with a coupler and the locking mechanism therefor, of a cylinder, a piston in said cylinder, a valve, and means whereby the movement of the piston controls the coupler-locking mechanism, substantially as and for the purposes specified.

11. In a coupler-release rigging, the combination with a coupler and the locking mech-

- anism therefor, of a cylinder, a piston in said cylinder, a valve having a leak, and means whereby the movement of the piston controls the coupler-locking mechanism, substantially as and for the purposes specified.
12. In a coupler-release rigging, the combination with a coupler and the locking mechanism therefor, of a cylinder, a piston in said cylinder, means for actuating said piston, means for retarding the movement of the piston in one direction, and means whereby the movement of the piston controls the coupler-locking mechanism, substantially as and for the purposes specified.
13. In a coupler-release rigging, the combination with a coupler and the locking mechanism therefor, of a cylinder, a piston in said cylinder, means for actuating said piston, means for retarding the movement of the piston in one direction, means for releasing the retarding means, and means whereby the movement of the piston controls the coupler-locking mechanism, substantially as and for the purposes specified.
14. In a coupler-release rigging, the combination with a coupler and the locking mechanism therefor, of a cylinder, a piston in said cylinder, a spring acting upon said piston, and means whereby the movement of the piston controls the coupler-locking mechanism, substantially as and for the purposes specified.
15. In a coupler-release rigging, the combination with a coupler and the locking mechanism therefor, of a cylinder, a piston in said cylinder, a spring acting upon said piston, a valve in said cylinder, and means whereby the movement of the piston controls the coupler-locking mechanism, substantially as and for the purposes specified.
16. In a coupler-release rigging, the combination with a coupler and the locking mechanism therefor, of a cylinder, a piston in said cylinder, a spring acting upon said piston, a valve in said cylinder said valve provided with a leak, and means whereby the movement of the piston controls the coupler-locking mechanism, substantially as and for the purposes specified.
17. In a coupler-release rigging, the combination with a coupler and the locking mechanism therefor, of an uncoupling-lever, a cylinder, a piston in said cylinder, a rigid connecting member interposed between the uncoupling-lever and the piston, and means for actuating said piston, substantially as and for the purposes specified.
18. In a coupler-release rigging, the combination with a coupler and the locking mechanism therefor, of a cylinder, a piston in said cylinder, a valve automatically opened by the movement of the piston in one direction, means independent of said piston for opening said valve, and means whereby the movement of the piston controls the coupler-locking mechanism, substantially as and for the purposes specified.
19. In a coupler-release rigging, the combination with a coupler and the locking mechanism therefor, of a cylinder having a guideway adapted to receive a cross-head, a piston having a cross-head secured to the stem thereof, an uncoupling-lever, a rigid connection between the cross-head of said piston and said uncoupling-lever, a valve in said cylinder, and means whereby the movement of the piston controls the coupler-locking mechanism, substantially as and for the purposes specified.
20. In a coupler-release rigging, the combination with a coupler and the locking mechanism therefor, of a cylinder having a valve therein, a piston in said cylinder, an uncoupling-lever, a rigid connection between said piston and said uncoupling-lever, and a spring acting upon said piston and opposed to an uncoupling movement of said uncoupling-lever, substantially as and for the purposes specified.
21. In a coupler-release rigging, the combination with a coupler and the locking mechanism therefor, of an uncoupling-lever adapted to actuate a piston in one direction, a piston, and means whereby the piston controls the return movement of said uncoupling-lever, substantially as and for the purposes specified.
22. In a coupler-release rigging, the combination with a coupler and its locking mechanism, of a mobile medium, a receptacle therefor, a leak for the transfer of the mobile medium, and means operated by the transfer of the mobile medium for actuating the locking mechanism of the coupler, substantially as and for the purposes specified.
23. In a coupler-release rigging, the combination with a coupler and its locking mechanism, of a cylinder and its piston, a valve, and a leak, and means for actuating the locking mechanism of the coupler from the piston of the cylinder, substantially as and for the purposes specified.
24. In a coupler-release rigging, the combination with a coupler and its locking mechanism, of a cylinder and its piston, a leak, means for actuating the piston of the cylinder, and means for actuating the locking mechanism of the coupler from the piston of the cylinder, substantially as and for the purposes specified.
25. In a coupler-release rigging, the combination with a coupler and its locking mechanism, of a mobile medium, a receptacle therefor, a leak for the transfer of the mobile medium, means for controlling the size of the leak, and means operated by the transfer of the mobile medium for actuating the locking mechanism of the coupler, substantially as and for the purposes specified.
26. In a coupler-release rigging, the combination with a coupler and the locking mech-

anism therefor, of means for controlling the period of the return movement of the locking mechanism to a locked position after the said locking mechanism has been set in an unlocked position, substantially as and for the purposes specified.

5 In testimony whereof I affix my signature,
